UNITED STATES PATENT OFFICE.

ARCHIBALD T. SAMPSON, OF LYNN, MASSACHUSETTS, ASSIGNOR TO SAMPSON AXCESS SYSTEM, INC., OF LYNN, MASSACHUSETTS, A CORPORATION OF MASSACHUSETTS.

PIPE-CUTTING MACHINE.

Application filed May 8, 1919, Serial No. 295,747. Renewed June 13, 1923.

To all whom it may concern:

Be it known that I, ARCHIBALD T. SAMPSON, a citizen of the United States, and a resident of Lynn, Massachusetts (whose post-office address is No. 494 Union St., Lynn, Massachusetts), have invented an Improvement in Pipe-Cutting Machines, of which the following description, in connection with the accompanying drawings, is a specification, like letters on the drawings representing like parts.

My present invention relates to cutting apparatus, and more particularly to cutting apparatus for cutting slots or openings in a metal conduit or pipe.

In my inventions upon an improved novel system of electrical construction and installation, partly explained in my prior co-pending application, Serial No. 166,813, filed May 7, 1917, one of the important features consists in a method of cutting partially through a metal conduit without injury to the electric wires therein, and even when the conduit is already in place in a building. In my co-pending application, Serial No. 345,284, filed December 16, 1919, I have described and claimed improved cutting apparatus for carrying out a step in the method described and claimed in my application, Serial No. 166,813, above referred to.

The cutting apparatus herein described and claimed is intended particularly for use in carrying out a further step in my improvements of forming the slot in a conduit or pipe for an outlet or tap, by partially cutting through the conduit or pipe. The cutting apparatus herein described and claimed is preferably used after the cutting apparatus described and claimed in my co-pending application, Serial No. 345,284 filed Dec. 16, 1919, has completed its operation, because a cleaner cut is made in this way, but the present invention and apparatus may be used to perform their functions at any time, regardless of whether or not the cutting apparatus described in the application above referred to has performed its function. While the present apparatus has been designed particularly for use on conduits or pipes already installed in a building or other structure, its use is not so limited, as it is equally capable of use in cutting slots in conduits or pipes before the same are installed.

A feature of my present invention is the

provision of a pivotally mounted oscillatory cutter for cutting a slot or plurality of slots transversely of a conduit or pipe, whether in position in a building or in a workshop.

Another feature of my invention is an improved feeding means for the cutters for feeding the same into and out of engagement with the work.

A further feature of my invention is an improved means for mounting the cutters, whereby the same are mounted parallel to each other at either side of the carrying means, and move together as a unitary structure.

A still further feature, and one relating to the last named feature, is the provision of improved means for mounting the entire cutting and feeding means on the body of the apparatus, together with means associated with said cutting and feeding means for co-acting with the body of the apparatus to hold the entire structure in operative position on the work.

Further important features, novel constructions, and arrangements of parts and advantages, will be hereinafter more fully pointed out and claimed.

In the accompanying drawings, illustrating a preferred embodiment of my invention:

Fig. 1 is a front elevation of the cutting apparatus, in position on a conduit or pipe;

Fig. 2 is a view of the upper portion of the cutting apparatus, with the cover plate removed to show the internal mechanism;

Fig. 3 is a sectional view on the line 3—3 of Fig. 2;

Fig. 4 is a detail showing the position occupied by the tool when in action;

Fig. 5 is a side elevation of the cutting apparatus, and

Fig. 6 is a sectional side elevation of the cutting apparatus on the line 6—6 of Fig. 1.

Referring to the drawings, and more particularly to Figs. 1, 5, and 6, 10 designates a body member, having the intermediate portion 11 thereof extending upwardly and provided at either side with clamping and bearing plates 12, these plates 12 being provided with grooves 13 which extend along their length, as designated in Figs. 5 and 6. The lower portion of the body member 10 has formed integral therewith a laterally extending portion 14, on either side of which, as viewed in Fig. 1, is an upwardly extend-

ing side plate 15, these plates 15 being rigidly attached to 14 by the bolt and nut 16 and 17.

Pivots attached to upper portions of 5 the side plates 15 are the ends of the arms 18 of the bell crank levers 19, the levers being tied together so as to move in unison by the rod 20 fastened to the ends of the arms 21 by the screws 22.

10 At the junction of the arms 18 and 21 of the bell crank lever 19 is pivotally mounted the lower end of a body member 23 having an intermediate portion 24 extending upwardly and provided at either side with 15 clamping and bearing plates 25, these plates 25 being provided with projections 8 which extend along their length, as designated in Figs. 5 and 6, and co-act with the grooves 13 in the plates 12. Pins 26, on the arms 21, 20 engage with the plates 15 to limit the downward movement of said arms 21. The construction just described constitutes a toggle joint for securely locking the members 25 and 12 together.

25 The projections 8 when brought into engagement with the grooves 13, and the arms 21 moved to their lowermost position, lock the body members 10 and 23 and associated parts, together, as clearly shown in Figs. 5 and 6. When in the position shown in Figs. 5 and 6, the body members are spaced apart and parallel to each other, as are the intermediate portions 11 and 24, these intermediate portions however, being spaced further 30 apart than the body members, for a purpose to be hereinafter described.

The lateral portion or projection 14 is internally screw-threaded at 27, to receive the externally threaded hollow shaft 28, the 40 path of travel of the shaft 28 being parallel to and equidistant from the body members 10 and 23. A handle 29, rigidly attached to the lower end of the hollow shaft 28, enables the operator to move the hollow shaft upward or downward.

The body member is provided with a guide way 30 in which slides a projection on a flange 31 of an internally threaded sleeve 32. This sleeve 32 is a free fit in the externally threaded hollow shaft 28 and extends downwardly to a point beyond the lower end of said hollow shaft, to provide room for a collar 33, which is held on the sleeve 32 by the pin 34 and limits the endwise movement 50 of the shaft 28. The upper part 35 only of the sleeve 32 is threaded to receive the threaded portion of the feed rod 36. The lower portion 137 of the interior of the sleeve 32 forms a bearing for the feed rod 36, the intermediate portion of the interior of the sleeve 32 being cut away, as shown in Fig. 6, to provide a clearance space for the threaded portion of the feed rod when the same is lowered in the sleeve 32.

60 The upper portion 37 of the feed rod 36

is reduced in diameter, as shown in Fig. 6, to receive a cross-bar 38 of a combined clamp and tool support. This cross-bar 38 extends laterally of the intermediate portions 11 and 24, as viewed in Fig. 1, and it is for the purpose of allowing room for the combined clamp and tool support that the space between the intermediate portions 11 and 24 is greater than the space between the body members 10 and 23. The feed rod 36 is provided with a handle 70 by means of which it may be turned. On the reduced portion 37 of the feed rod 36 and above the cross-bar 38 is rigidly mounted a gear 39 of any convenient diameter and pitch. The upper face of the cross-bar 38 is provided with holes 40 and 41, of suitable diameter and depth, parallel to and equidistant from the hole for the feed rod 36, to receive the lower ends of the auxiliary feed rods 42 and 43, respectively, to which are rigidly fastened gears 44 and 45 respectively, similar to the gear 39 as regards diameter and pitch. The upper portions of the auxiliary feed rods 42 and 43 are threaded, the pitch of this thread being equal to the pitch of the thread on the feed rod 36. In the drawings I have shown the thread on the feed rod 36 as right hand, and the threads on the auxiliary feed rods 42 and 43 as left hand, but it is to be understood that I may make the thread of the feed rod 36 left handed and the threads on the auxiliary feed rods 42 and 43 right handed, without departing from the spirit of the invention, the only requisite being that the gear 39 thereon, meshing with the gears 44 and 45, will turn the threaded auxiliary rods 42 and 43 in such a direction as to move the cross-bar 38 toward or from the clamping member 46, which is provided with longitudinally threaded holes 47, 48, and 49, to receive the feed rods 36, 42 and 43 respectively. Cover plates 71 for the gears 39, 44 and 45 and rods 37, 42 and 43 are provided, being held in position on the cross-bar 38 by screws 72. The upper end of the clamping member 46 is provided with V-shaped grooves 50 and 51, the extreme outer ends of which are provided with outwardly and upwardly extending projections 52, (as viewed in Fig. 6) 115 which are adapted to co-operate with the clamping arms 12 and 25. On the feed rod 36 beneath the cross-bar 38, is provided a nut 53 threaded onto the rod 36 and between the upper end of this nut and the lower face of the cross-bar is a coil spring 54 and the collar 55 which is preferably formed integral with the nut 53. The tension of the spring 54 is adjusted by moving the nut 53 on the feed rod 36, and the nut is held in 120 adjusted position by the screw 56. This construction allows the cutting mechanism on the cross-bar 38 to be yieldingly held against the pipe being worked on, as there is ample 125 space or clearance between the lower face of 130

the cross-bar 38 and the top of the collar 55 when the spring 55 is fully compressed, as is evident from an inspection of Fig. 6.

Centrally located on either end of the cross-bar 38 are laterally projecting studs 57 and 58, on which are pivotally mounted the cutter holders 59 and 60 respectively. The cutter holders are composed of plates 61 and 62, each being provided on their inner face with centrally located longitudinal grooves 63 in which is placed the cutter 64. Near the upper end of the plates 61 and 62 of the cutter holders are aligned perforations on either side of their longitudinal center, to receive the reduced threaded ends of the rods 65 and 66. Nuts 67 clamp the plates 61 and 62 firmly to the rods 65 and 66, this operation also clamping the cutter 64 in position in the grooves 63 in the plates. The portions of the clamping member 46 containing the V-shaped grooves 50 and 51 are perforated, as at 68, to allow the cutters 64 to be fed therethrough into engagement with the conduit or pipe to be worked on.

The distance between the parallelly arranged rods 65 and 66 is greater than the thickness of the clamping member 46 at this point, being equal to the depth of the cutters 64, so that, as the cutter bars 59 and 60 oscillate on the studs 57 and 58 respectively, the operative cutting edge of the cutter will be in line with the line joining the center of the pipe 69, being worked on, and the center of the studs 57 and 58, as clearly shown in Fig. 6. By this construction a straight parallel-sided cutter 64 may be used with the assurance that there will always be proper clearance for the cutting edge, as clearly shown in Fig. 4. When the cutter requires sharpening, the top end only of the cutter need be ground.

The operation of my invention is as follows:

The feed rod 36 is rotated to lower the upper face of the cutters 64 below the V-shaped grooves 50 and 51. The arm 21 is raised to unlock the toggle joint, and disengage the projection 8 from the groove 13. The clamping and bearing faces 12 are placed over the conduit or pipe to be operated on, the projection 8 dropped into the groove 13, and the body members 10 and 23 and associated parts locked together by depressing the arm 21. Handle 29 is now turned to rotate the hollow shaft 28, moving the feed rod 36 and all mechanism associated therewith upward until the V-shaped grooves 50 and 51 engage with the lower portion of the pipe 69. I assume that the cutting apparatus of the present invention is to be used after the longitudinal grooves or slots have been cut in the conduit or pipe by the cutting apparatus described and claimed in my co-pending application Serial No. 345,284, filed Dec. 16, 1919. The appa-

ratus of the present invention is therefore, moved along the conduit or pipe until in proper position with relation to the longitudinal slots referred to, when the handle 70 is operated to turn the feed screw 36 and raise the cutters upward into engagement with the conduit 69. The entire mechanism is now oscillated on the conduit or pipe making two parallel cuts extending from one longitudinal slot to the other. After the first cut or stroke is made, the cutters 64, working in the cuts, prevent any movement of the cutting apparatus along the pipe.

The cutters 64 are made of commercial size tool steel rod, rectangular in cross-section, and of any suitable length. As the cutting edge becomes dulled, the cutter may be sharpened by simply grinding the end thereof, and it may be thus sharpened indefinitely until the rod is too short to be acted on by the clamping bolts 65 and 66 and nuts 67. This type of tool and tool holder is extremely practical and economical, as it has been found that the cutter may be used until it is less than three quarters of an inch in length.

The drawings illustrate one embodiment of my invention, and it is to be understood that I may vary the size, shape, and arrangement of the elements shown without departing from the spirit of the invention. While I have shown the apparatus embodying a plurality, i. e. a pair of cutting cutters, it will be appreciated that the invention, broadly considered, may be embodied with a single cutter or with a greater plurality of cutters than the pair herein shown. Furthermore, an important feature of this apparatus consists in the fact that the cutter oscillates from one cutting position to the reverse during the oscillation of the entire apparatus, consequently each cutter presents two cutting corners or edges and these cutting edges are automatically brought into cutting operation through the oscillation of the cutters,—this is on the pivots 57 and 58 during the normal operation of the entire apparatus through the swinging to and fro of the handle 70. This feature is most important, greatly increasing the life of the cutters and insuring the quick cutting action automatically digging in each corner of the tool to increase the line of cut. A further important feature is the fact that the portions 52 constitute a guard or guide for the depth of cutting action of each cutter, these portions 52 contacting with the outer face of the pipe at different relative positions proportionately determined by the diameters of the pipe being acted upon. I believe this action to be a distinct novelty in this art and I wish to claim the same broadly.

An additional important feature of the machine is the automatic adjustment of each

cutter and guard for different diameters of pipe, and with a large range—from one-half inch diameter to an inch and a half diameter, five sizes of pipe for which a single machine is capable of operating upon.

Having thus described my invention, what I claim and desire to secure by Letters Patent, is:—

1. A machine of the class described adapted for forming spaced cuts, having a pair of pivotally mounted cutters provided with cutting edges at either side thereof, means for oscillating said cutters on their pivot points to bring said cutting edges alternately into cutting position, and means for moving said cutters into and out of engagement with the work, in combination with means to hold the work and cutters into operative engagement.
2. A machine of the class described adapted for forming parallel cuts simultaneously transversely of a cylindrical rod or pipe, having a pair of pivotally mounted cutters provided with cutting edges at either side thereof, means for oscillating said cutters on their pivot points to bring said cutting edges alternately into cutting position, means to move said cutters into and out of engagement with the work, simultaneously, and means for yieldingly holding said cutters against the work.
3. A machine of the class described, comprising a body having hinged members, means for locking the hinged members together to suspend the body on the conduit or pipe, a hollow shaft, movable longitudinally of the body, a feed screw mounted for rotation and longitudinal movement in said hollow shaft, a plurality of cutters mounted on said feed screw, auxiliary clamping or positioning means also mounted on said feed screw, and means for moving said hollow shaft longitudinally of the body to position the auxiliary clamping or positioning means and said cutters on the conduit or pipe.
4. A machine of the class described, including a body member and means associated therewith for positioning the machine on the work, a cross-bar located below and parallel to said associated means, oscillatory cutter holders pivotally mounted at their lower ends on either side of said cross-bar, and means near the upper end of the cutter holders for connecting the same and limiting the oscillatory movement thereof.
5. A machine of the class described, including a body member and means associated therewith for positioning the machine on the work, a cross-bar located below and parallel to said associated means, oscillatory cutter holders pivotally mounted at their lower ends on either side of said cross-bar, means near the upper end of the cutter holders for connecting the same and limiting the

oscillatory movement thereof, and perforations in said associated means through which the upper end of the cutter bars may extend.

6. A machine of the class described, including a body member and means associated therewith for positioning the machine on the work, a cross-bar located below and parallel to said associated means, oscillatory cutter holders pivotally mounted at their lower ends on either side of said cross-bar, means near the upper end of the cutter holders for connecting the same and limiting the oscillatory movement thereof, a plurality of parallel threaded shafts rotatably mounted in said cross-bar and engaging in threaded holes in the said associated means, gears mounted on said threaded shafts and engaging with each other so that the shafts rotate at the same speed and simultaneously, and means for rotating one of said shafts.

7. A machine of the class described adapted for forming cuts simultaneously transversely of a cylindrical rod or pipe, including a cross-bar, a pair of cutters pivotally mounted, means for oscillating said cutters on their pivot points, a threaded feed rod, a gear thereon, a rotatable threaded rod parallel to and on either side of said feed rod, gears on said parallel rods equal in diameter and pitch to the gear on the feed rod, whereby the parallel rods are rotated at the same speed as the feed rod, a positioning bar into which said parallel rods and feed rod are threaded, and means for rotating said feed rod whereby the cross-bar is moved parallel to and towards and away from the positioning bar.

8. A machine of the class described adapted for forming parallel cuts simultaneously transversely of a cylindrical rod or pipe, including a cross-bar, a pair of cutters pivotally mounted, means for oscillating said cutters on their pivot points, a threaded feed rod, a gear thereon, a rotatable rod parallel to and on either side of said feed rod, the threads on said parallel rods being of the same pitch but of opposite direction to the thread on said feed rod, gears on said parallel rods equal in diameter and pitch to the gear on the feed rod, whereby the parallel rods are rotated at the same speed as the feed rod, a positioning bar into which said parallel rods and feed rod are threaded, and means for rotating said feed rod, whereby the cross-bar is moved parallel to and towards and away from the positioning bar.

9. A machine of the class described for forming parallel cuts simultaneously transversely of a cylindrical rod or pipe, including a feed rod, a cross-bar thereon, cutters carried by said cross-bar, adjustable means on said feed rod, a spring on said feed rod below the cross-bar, and means on said feed

130

rod for adjusting the tension of said spring.

10. A machine of the class described for forming parallel cuts simultaneously transversely of a cylindrical rod or pipe, comprising means for suspending the machine from the rod or pipe in position, means for co-acting therewith to hold the machine in position on the rod or pipe, a plurality of yieldingly mounted oscillating cutters provided with cutting edges at either side thereof, said cutters operating in unison to cut a plurality of parallel slots in a rod or pipe, and means for oscillating said cutters to bring the cutting edges alternately into cutting position and moving them into and out of engagement with the rod or pipe being worked on.

11. A machine of the class described, adapted for cutting a slot in a cylindrical rod or pipe transversely of the length thereof, including a pivotally mounted two-edged cutter, means for mounting said cutter on the rod or pipe, and means for oscillating said cutter on its pivot to bring the cutting edges alternately into cutting position.

12. A machine of the class described, adapted for cutting a slot in a rod or pipe transversely of the length thereof, including a support, a two-edged cutter pivotally mounted thereon, means on the support for attaching the machine to the rod or pipe, and means for oscillating said cutter on its pivot to bring the cutting edges alternately into cutting position.

13. A machine of the class described having a cutting member, clamping means to hold said member into cutting engagement with the working means, said clamping means cooperating with the cutting member to automatically cause alternate cutting portions of the cutting member to be presented to the work during the oscillation of the apparatus.

14. A machine of the class described, having a pivoted cutting member, clamping means to hold said member into cutting engagement with the work, means providing for the oscillation of the cutting member and cooperating with a to and fro swinging movement of the machine whereby opposite cutting corners in said member are automatically brought into successive work cutting engagement during the oscillation of the apparatus.

15. In a machine of the class described, a cutting tool adapted to cut a groove in work during the oscillating movement of the apparatus comprising a pivotal mounting for said cutting tool, means permitting predetermined independent oscillation of the cutting tool during oscillation of the apparatus and means to increase the depth of cut at will.

16. Pipe cutting apparatus of the kind

described having a pivotally mounted cutter, a plurality of cutting edges on said cutter, and means to successively bring different cutting edges into work engaging position through oscillation of the apparatus, in combination with means to hold the apparatus in work engaging position on the pipe.

17. Pipe cutting apparatus comprising a pivotally mounted cutting tool, and pipe engaging means to hold the apparatus into work engaging position with the pipe, including clamping devices to cooperate with the cutting tool and limit the depth of cut, in combination with adjustable cutter feeding means to increase the depth of cut of the cutter independently of the clamping members.

18. Pipe cutting apparatus having pipe engaging members, a cutting tool adapted to oscillate between said pipe engaging members and means to automatically bring successive edges into cutting position by the oscillation of the pipe cutting tool relatively with the engaging members during the operation of the apparatus.

19. Pipe cutting apparatus having pipe engaging members, a cutting tool adapted to oscillate between said pipe engaging members and means to automatically bring successive edges into cutting position by the oscillation of the pipe cutting tool relatively with the engaging members during the operation of the apparatus, in combination with means to predetermine the extent of oscillation of said cutting tool relatively with the pipe engaging members.

20. A machine of the class described, adapted for completing the cutting of a slot in a cylindrical rod or pipe, including a plurality of pivotally mounted two-edged cutters, spaced apart for completing the slot cutting action transversely of the length of the pipe, means for oscillating said apparatus relatively with the pipe to bring the cutters into action and means for simultaneously feeding forwardly the said plurality of cutters to increase the depth of cut.

21. A machine of the class described, adapted for cutting a slot in a cylindrical rod or pipe, transversely of the length thereof, including cutting means adapted for effecting a cutting action in alternate directions during relative movement of said cutting means and the pipe.

22. A machine of the class described, adapted for cutting a slot in a cylindrical rod or pipe, transversely of the length thereof, including a plurality of oscillating cutters adapted for effecting a cutting action in alternate directions during relative movement of said plurality of oscillating cutters and the pipe.

23. Pipe cutting apparatus having pipe engaging clamping members, a plurality of pivotally mounted cutting tools mounted

for oscillation independent of any movement imparted to the clamping members, and means automatically determined by the diameter of the pipe and by the action of the clamping members to position the plurality of cutting tools in operative alignment and engagement with the pipe.

In testimony whereof, I have signed my name to this specification, in the presence of two subscribing witnesses.

ARCHIBALD T. SAMPSON.
